UNITED STATES PATENT OFFICE

REN L. FRIST, OF DANA, INDIANA

WALL SPACER FOR CONCRETE FORMS

Application filed July 3, 1931. Serial No. 548,681.

The present invention relates to a spreader or spacer for concrete forms particularly those which are too deep or/and narrow for workmen to remove spreaders or spacers 5 from the outside or top of the form.

The prime object of the invention resides in the provision of a device of this nature which may be easily removed even though situated at a distance from the top of the 10 form.

Another very important object of the invention resides in the provision of a device of this nature which is exceedingly simple in its construction, thoroughly efficient and reliable in use, easy to manipulate, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described.

In the drawings:

25 Figure 1 is a sectional view through a form showing one of my devices in place.

Figure 2 is a top plan view thereof.

Figure 3 is a longitudinal section through one of the devices.

30 Figure 4 is a perspective view of an outer section of the device,

Figure 5 is a perspective view of a tool to manipulate the device, and

Figure 6 is an enlarged detail section 35 taken substantially on the line 6-6 of Figure 1.

Referring to the drawings in detail it will be seen that numeral 5 denotes the opposed wall of a concrete form. A plurality of my 40 improved spreading or spacing devices will be used but a detail description of one will suffice for all. Each device comprises a pair of sections A and B. Section A includes a channel member 6 slidably receiving a channel member 7. The channel member 7 has its side formed with a plurality of openings 8 to receive bolts 9 which extend through the sides of the member 6 thereby allowing the section A to be lengthened or shortened as 45 may be required. Little pointed nibs 10 pro-

ject from the outer ends of the sides of the member 7. The inner ends of the sides of the member 6 are provided with apertured ears 11.

Section B comprises a member 12 and a 55 member 14 both of channel construction and formed with pluralities of openings 15 in their sides to receive bolts 16 so that the length of the section B may be lengthened or shortened as required. From the outer 60 ends of the sides of the member 14 there project pointed nibs 17. Intermediate portions of the sides of the member 12 are formed with apertured ears 18. A bolt 19 extends through apertured ears 18 and 11, 65 the ears 18 being to the outer side of the ears 11. A spacer sleeve 20 is disposed circumjacent the bolt 19 between the ears 11. On the inner end of the member 12 is an inverted U-shaped member or bail 22 with 70 which a hook tool 23 may be engaged.

After the sections A and B have been adjusted to the desired length the device is placed between the walls 5 somewhat in the angular position shown in Figure 3 and 75 then the center of the device is forced downwardly to spread the walls apart the desired distance at which time the sections are aligned as shown clearly in Figure 1. No matter how far down in the form the device 80 may be, a suitable tool 23 of proper length may be extended down so that the hook end may engage the bail 22 and then by pulling up on the tool the device may be broken from the position shown in Figure 1 to the 85 position shown in Figure 3 and easily pulled out of the form.

It will be also noted that the sections 6 and 12 at their outer ends are provided with 90 nibs similar to the nibs 17 so that if the width of the work is such as to permit of dispensing with the sections 7 and 14 the outer ends of the sections 6, 12 will engage the walls 5 in substantially the same manner as the outer ends of the sections 7 and 14 95 are adapted to engage the walls as above stated. It will be also noted that each of the sections 6, 7, 12 and 14 at its outer end has the sides thereof extended downwardly forming projections or abutments 24 to en- 100

gage the inner side of the walls 5 as shown in Figure 1. It will be also noted that in providing the abutments 24 edges 25, 26 of material length are provided at the outer 5 ends of the sections above and below the pointed nibs for flat contact with the inner faces of the walls 5 as is also shown in Figure 1.

It is thought that the construction, operation, utility and advantages of this invention will now be quite apparent to those skilled in this art without a more detailed description thereof.

The present embodiment of the invention 15 has been described in considerable detail merely for the purposes of exemplification since in actual practice it attains the features of advantage enumerated as desirable in the statement of the invention and the 20 above description.

It will be apparent that changes in the details of construction, and in the combination and arrangement of parts may be resorted to without departing from the spirit 25 or scope of the invention as hereinafter claimed or sacrificing any of its advantages.

Having thus described my invention, what I claim as new is:

1. A device of the character described comprising a pair of pivoted sections, each of which include a pair of channel shaped members telescopically engaged one with the other, means for securing the telescoped 70 members in adjusted position relative to one another, and each of said members having the sides at one end thereof provided with integral depending projections forming abutments and being also provided with 75 pointed nibs extending longitudinally from said sides.

2. In a device of the character described, a pair of sections pivoted together, each of said sections comprising a channel shaped 80 member, means pivotally connecting one end of one of said members with the other of said members inwardly from the ends of said other member, and each of said members at its free end having the sides thereof 85 provided with depending abutments and being also provided at their end edges with pointed nibs extending longitudinally from said sides.
